DESIGN FOR A PYROPHORIC LIGHTER, OR SIMILAR ARTICLE

Joseph Bonfield, Brooklyn, N. Y., assignor to
Wayne Industries, Inc., Brooklyn, N. Y., a cor-
poration of New York

Application December 3, 1947, Serial No. 142,939

Term of patent 14 years

(Cl. D48—27)

To all whom it may concern:

Be it known that I, Joseph Bonfield, a citizen of the United States of America and a resident of Brooklyn, in the county of Kings, city and State of New York, whose post-office address is 224 Highland Boulevard, Brooklyn, New York, have invented a new, original, and ornamental Design for a Pyrophoric Lighter, or Similar Article, of which the following is a specification, reference being had to the accompanying drawing, forming a part thereof, in which:

Figure 1 is a front elevational view of a pyrophoric lighter, or similar article, showing my new design, with the collar in the "up" or closed position;

Fig. 2 is a front elevational view with the collar in the "down" or open position;

Fig. 3 is a side elevational view thereof with the collar in the "down" or open position; and

Fig. 4 is a rear elevational view thereof with the collar in the "down" or open position.

I claim:

The ornamental design for a pyrophoric lighter, or similar article, as shown.

JOSEPH BONFIELD.
